6 Claims. (Cl. 103—44)

1

The present invention relates to a pump for raising petroleum and other liquids from deep wells and has for its object to eliminate the use of mechanical transmission elements which are so objectionable in view of the unavoidable friction occurring between the members which are guided within the piping for the purpose of actuating the piston.

In fact, as is well known, in plant for extracting liquids in which the latter exceed several times the equivalent atmospheric column, the pistons are actuated by a mechanical transmission comprising a rod which, however centrally it may be disposed, will inevitably bend and become displaced at some part of its length, so that the consequent wear will shorten the life not only of the movable member or transmission rod but also of the piping which is so expensive both in itself and by reason of the complexity of its application. Since other mechanical transmission pistons would have consequences which are similar to those just pointed out, investigations have been made along the lines of hydraulic transmission, and although at first certain difficulties were encountered a satisfactory result has finally been reached, since by means of a simple pipe in closed circuit with the suction pipe, this important problem has been solved with considerable attendant advantages from every point of view. The combination of the hydraulic transmission on which the present invention is predicated is embodied by two piston members one of which acts as control member and is located in the upper portion coupled to the windmill or other source of power, whereas the other piston member is adjacent the well, the arrangement being such that through a secondary branch pipe said other piston member is hydraulically moved by the liquid transmitted thereto by the control member, that is to say, in the suction phase, because in the back or downward stroke the actuated piston member responds directly to the effect of the hydraulic column of the suction pipe.

In addition to the foregoing the present invention has a number of objects, amongst which may be pointed out that of being able to operate with the pump at any depth without any counter-effects, since the hydraulic circuit functions with the same response as well at short as at long distances.

Another object of this invention is to enable the apparatus to be installed in any direction that is to say, with bends or twists resulting from the convenience of the structural conditions and the location of the strata of liquid, and this is

2

very advantageous both for petroleum extraction plants and for pumping water.

Another object is to obtain greater lightness in the piston movements, since, because the system is hydraulic there is no need to support the weight of transmissions members as is the case with rods extending to great depths. These and other objects and advantages of the present invention will become apparent in the course of the description thereof which for greater clarity and readier understanding has been illustrated by several figures in which the lifting pump is shown by way of example in one of its preferred embodiments in the drawing.

15 Figure 1 is a vertical section of the pump assembly.

Figure 2 is a section showing graphically the downward stroke of the control piston and how the actuated piston member is caused to descend.

20 Figure 3 illustrates the end of the downward stroke of the control piston which causes the actuated piston member to reach its lowermost point, where it is ready immediately to commence the upward stroke, and finally;

25 Figure 4 shows graphically how during the upward stroke of the control piston the liquid flows through the secondary branch to the lower parts of the actuated piston member which thus ascends thereby exerting suction on the water and raising the column the surplus of which emerges from the delivery pipe.

30 In the several figures the same reference characters indicate like or corresponding parts or elements. Devices or elements comprising several parts are indicated by reference letters.

35 As may be seen in the drawings, *a* is the lifting column which as usual is composed of a pipe which extends down until it reaches the well. The rod *2* which may be the power rod of a windmill or any other source of power, passes through the gland *3* and into the first section of the column *a* which forms the pump cylinder *4*, in which the piston *b* acts, said piston being connected to rod *2* and being hereinafter referred to as the control piston.

40 As in all pumps, the column *a* ends with the liquid inlet *5* which is an orifice having a check valve *6* and adjacent said inlet *5* is the cylinder *7* and beyond the latter there is a cylinder *8* both these cylinders *7* and *8* forming part of the column *a*.

45 The cylinder *7* is smaller than the cylinder *8* but is in coaxial alignment therewith as if forming a single cylinder of two bodies.

50 In these two cylinders *7* and *8* the actuated pis-

ton assembly *c* operates, the length of this assembly being sufficient for the lower portion with the smaller piston *9* to operate in the cylinder *7* whereas at the upper end of the same piston assembly the larger piston *10* operates in the cylinder *8*.

The difference in diameter between the piston *9* and piston *10* of the assembly *c* corresponds to the diameter of the control piston *b*.

From the upper part of the column *a* that is to say at the upper end of the cylinder *4*, projects a branch pipe *11* which extends in general parallel to the column *a* downwardly to the lower portion thereof and is connected to the cylinder *8* at its lowermost portion, that is to say at the point *8'* so that the water or liquid flowing through said branch pipe may enter said part or space *8'* of the cylinder *8* and operate against the annular shoulder *10'* of the piston *10*.

The actuated piston assembly *c*, as regards the piston *9*, has a check valve *12* so that when said assembly is forced up by the pressure of liquid from branch *11*, the piston *9* shall suck up from the well *1* the liquid which enters by the inlet *5* when the valve *6* unseats. The raising column *a* has a lateral aperture *13* wherethrough liquid may flow through the outlet pipe *14* extension to the receiver or service line to which said liquids has to be delivered.

Aperture *13* has a seat *13'* with which a valve *15* is adapted to coact, said valve opening inwardly of the column *a*.

The branch pipe *11* likewise has an aperture *16* which, similarly to the aperture *13*, also gives access to the pipe *14* and has a seat *16'* and includes a valve *17* adapted to open inwardly of the branch *11* and rigidly connected to the valve *15* by means of the tie rod *18*. Said tie rod is longer than the distance between the seats *13'* and *16'* thereby allowing play to the valves *15* and *17* so that when one of said valves is closed and the other is open and vice versa, in response to the direction of the pressure in column *a* or branch *11*. The valve member constituted by the valves *15* and *17* connected by the rod *18* is indicated in general by the reference letter *d*.

The piston *b* has an opening *19* with a valve *20* normally held closed by a spring *21*, the strength of said spring being such that during the downward stroke of piston *b* the spring will not yield at any point of that stroke in spite of the work being done, since as already has been stated, the piston *b*, in descending, drives the liquid column downwards thereby compelling the piston *c* to do likewise that is to descend proportionally. If, however, the piston assembly *c* reaches the bottom of its stroke and engages the stop *22* of the valve *6*, since the liquid cannot escape through any other point, pressure increases in column *a* until it overcomes the resistance of spring *21*, whereupon, as indicated in Fig. 3, said liquid passes into the upper portion of the same column which is in communication with the branch *11*.

The branch pipe *11* has a safety valve *e* with a closure member *23* urged normally to closed position by the spring *24*, the pressure of which may be adjusted by the screw *25*. The safety valve is adjusted to yield at a predetermined pressure and allows liquid to escape through the orifices *26*, if for any reason the pressure in the branch *11* becomes higher than normal.

The branch pipe *11* has a priming opening *27* normally closed by a plug *28*, or said branch may

be coupled to any suitable priming device, that is to say a means adapted to provide a quantity of liquid sufficient to fill the piping of the pump as a whole.

Operation

When the pump has been primed as indicated through the priming opening *27*, on starting up the windmill or other apparatus which actuates the rod *2*, the piston *b* if in the upper part of its stroke, will move downwardly driving down the column of liquid contained in the pipe *a*. As a result of this, the aperture *13* is closed by the valve body *15* whereas aperture *16* is opened by the displacement of the device *b* as a whole. Since the piping corresponding to the column *a* is thus closed the liquid in cylinder *8* exerts pressure against piston *10* of the assembly *c* since said piston offers a greater receptive surface than the cross sectional area of the passage of the axial bore *29* which extends from end to end of the assembly *c*.

For these reasons as the control piston *b* moves downwardly it forces the actuated assembly *c* to move downwardly as well, as indicated in Fig. 2, thereby displacing the liquid from the lower space *8'* of cylinder *8*, said liquid being displaced into the branch pipe *11*. As graphically shown in the same figure, when the assembly *c* thus descends the liquid which is in the cylinder *7* finds its way past the valve *12* and the passage *29* into the cylinder *8*.

As hereinbefore stated, at the end of the downward stroke of the actuated assembly *c* in response to actuation of the control piston *b*, if the former engages the stop *22* as shown in Fig. 3 the pressure caused by the effect of the closure overcomes the resistance of the spring *21*, the liquid then passing to the upper portion of column *a* which is in communication with the branch *11*.

Thereupon when the control piston *b* rises as shown in Fig. 4, it acts with its upper portion to exert a thrust on the liquid whereby said liquid is forced into the branch *11* creating a pressure which forces the assembly *b* to become displayed, thereby closing the valve *17* and opening valve *15*. With the branch *11* thus closed, the liquid entering the space *8'* of cylinder *8* exerts pressure against the shoulder *10'* of the piston *10*, thus forcing the actuated assembly *c* to move upwardly as also indicated in Fig. 4. This upward movement on the one hand causes the assembly *c* through the piston *9*, to exert suction on the water in the well *1* which forces its way past the valve *6*, and, on the other hand, the liquid which was previously in column *a* is moved up therein and as its volume is greater than that of the space left by the retreating control piston *b*, the excess flows out through aperture *13* since this is open, as is also shown in Fig. 4. In this way, the said excess liquid provided by the operation of the pump and flowing through the discharge pipe *14* reaches the tank or service point.

On the conclusion of the upward stroke, the control piston *b* again moves downwardly closing valve *15* and forcing the actuated assembly *c* to move down as illustrated in Fig. 2 until it reaches the stop indicated in Fig. 3. These cycles are repeated in succession with the corresponding reciprocatory movement, since with the hydraulic charge an oscillatory circuit properly so called is obtained.

It is to be understood that in carrying the invention into practice I may modify the same with

regard to details of construction and form of the pump described, without however thereby departing from the fundamental principles clearly set forth in the accompanying claims.

I claim:

1. A pump for raising petroleum and other liquids from deep wells comprising a source of power, a hydraulic alternating flow circuit including a suction pipe, a branch pipe, valved means interconnecting the suction pipe and the branch pipe, a delivery pipe communicating with said valved means, said branch pipe including priming means and safety valve means, said suction pipe including on one side of said valved means a control cylinder and a control piston reciprocable in said control cylinder, an orifice in said control piston and a spring urged valve member normally closing said orifice, fluid means for said control piston, said control piston being connected to said source of power and on the other side of said valved means a relatively larger diameter cylinder and major piston head reciprocable in said larger diameter cylinder, and a smaller diameter cylinder disposed beyond said alternating flow circuit in intercommunicating end to end relationship with said larger diameter cylinder, said piston head being coupled together and forming an actuated piston assembly, an axial passage extending through said assembly, check valve means at one end of said passage, fluid inlet means at the end of the smaller diameter cylinder remote from the larger diameter cylinder and check valve means normally closing said fluid inlet means.

2. A pump for raising oil or other liquids from deep wells comprising a suction pipe including a cylinder of relatively large diameter and a cylinder of relatively small diameter arranged in intercommunicating end to end relationship; a major piston reciprocable in said larger diameter cylinder and a minor piston reciprocable in said smaller diameter cylinder, both pistons being coupled together to form an actuated piston assembly, a liquid inlet at the free end of said smaller diameter cylinder; a check valve for said inlet; a passage communicating the free end of said smaller diameter cylinder with the free end of said larger diameter cylinder; a check valve for said passage; a control cylinder and a piston reciprocable therein; said last mentioned piston being connected to a source of power; a passage communicating one end of said control cylinder with the free end of said larger diameter cylinder, a branch pipe communicating the other end of said control cylinder with the suction pipe at a point intermediate the larger diameter cylinder and the smaller diameter cylinder; a passage communicating one end of said control cylinder with the other end thereof; a valve member resiliently urged into a position in which it closes said last-mentioned passage; a discharge pipe in communication with the free end of said larger diameter cylinder; a check valve for said communication; a passage communicating said discharge tube with that end of the control cylinder opposite to the end communicating with the larger diameter cylinder; a check valve for said passage.

3. A pump for raising oil or other liquids from deep wells comprising a suction pipe including a cylinder of relatively large diameter and a cylinder of relatively small diameter arranged in intercommunicating end to end relationship; a major piston reciprocable in said larger diameter cylinder and a minor piston reciprocable in

said smaller diameter cylinder, both pistons being coupled together to form an actuated piston assembly; a liquid inlet at the free end of said smaller diameter cylinder; a check valve for said inlet; a passage communicating the free end of said smaller diameter cylinder with the free end of said larger diameter cylinder; a check valve for said passage; a control cylinder and a piston reciprocable therein; said last-mentioned piston being connected to a source of power; a passage communicating one end of said control cylinder with the free end of said larger diameter cylinder; a branch pipe communicating the other end of said control cylinder with the suction pipe at a point intermediate the larger diameter cylinder and the smaller diameter cylinder; a longitudinal passage in said control cylinder; a valve member resiliently urged into a position in which it closes said last-mentioned passage; a discharge pipe in communication with the free end of said larger diameter cylinder; a check valve for said communication; a passage communicating said discharge tube with that end of the control cylinder opposite to the end communicating with the larger diameter cylinder; a check valve for said passage.

4. A pump for raising oil or other liquids from deep wells comprising a suction pipe including a cylinder of relatively large diameter and a cylinder of relatively small diameter arranged in intercommunicating coaxial end to end relationship; a major piston reciprocable in said larger diameter cylinder and a minor piston reciprocable in said smaller cylinder; both pistons being coupled together to form an actuated piston assembly; a liquid inlet at the free end of said smaller diameter cylinder; a check valve for said inlet; a passage communicating the free end of said smaller diameter cylinder with the free end of said larger diameter cylinder; a check valve for said passage; a control cylinder and a piston reciprocable therein; said control cylinder, arranged in intercommunicating coaxial end to end relationship with said larger diameter cylinder, a branch pipe communicating the free end of said control with the suction pipe at a point intermediate the larger diameter cylinder, a passage communicating one end of said control cylinder with the other end thereof; a valve member resiliently urged into a position in which it closes said last-mentioned passage; a discharge pipe in communication with the free end of said larger diameter cylinder; a check valve for said communication; a passage communicating said discharge tube with that end of the control cylinder opposite to the end communicating with the larger diameter cylinder; a check valve for said passage.

5. A pump for raising oil or other liquids from deep wells comprising a suction pipe including a cylinder of relatively large diameter and a cylinder of relatively small diameter arranged in intercommunicating coaxial end to end relationship; a major piston reciprocable in said larger diameter cylinder and a minor piston reciprocable in said smaller cylinder, both pistons being coupled together to form an actuated piston assembly; a liquid inlet at the free end of said smaller diameter cylinder; a check valve for said inlet; a passage communicating the free end of said smaller diameter cylinder with the free end of said larger diameter cylinder; a check valve for said passage; a control cylinder and a piston reciprocable therein; said control cylinder arranged in intercommunicating coaxial end to end

relationship with said larger diameter cylinder, a branch pipe communicating the free end of said control with the suction pipe at a point intermediate the larger diameter cylinder and the smaller diameter cylinder, a passage communicating one end of said control cylinder with the other thereof; a valve member resiliently urged into a position in which it closes last-mentioned passage; a passage communicating said branch pipe with the suction pipe at point intermediate the larger diameter cylinder and the control cylinder; a check valve in either of the ends of said last-mentioned passage, adapted to close either end of said passage when the opposite end thereof is open; said passage being communicated to a discharge tube.

6. A pump for raising oil or other liquids from deep wells comprising a suction pipe including a cylinder of relatively large diameter and a cylinder of relatively small diameter arranged in intercommunicating end to end relationship; a major piston reciprocable in said larger diameter cylinder and a minor piston reciprocable in said smaller diameter cylinder, both pistons being coupled together to form an actuated piston assembly; a liquid inlet at the free end of said smaller diameter cylinder; a check valve for said inlet; an axial passage extending through said piston assembly, a check valve in said axial passage; a control cylinder and a piston reciproca-

ble therein; said last-mentioned piston being connected to a source of power; a passage communicating one end of said control cylinder with the free end of said large diameter cylinder; a branch pipe communicating the other end of said control cylinder with the suction pipe at a point intermediate the larger cylinder and the smaller diameter cylinder; a passage communicating one end of said control cylinder with the other end thereof; a valve member resiliently urged into a position in which it closes said last-mentioned passage; a discharge pipe in communication with the free end of said larger diameter cylinder; a check valve for said communication; a passage communicating said discharge tube with that end of the control cylinder opposite to the end communicating with the larger diameter cylinder; a check valve for said passage.
